US00D936114S

(12) **United States Design Patent** (10) **Patent No.:** **US D936,114 S**
(45) **Date of Patent:** **** Nov. 16, 2021**

(54) **OPERATOR STATION FOR WORK VEHICLE**

(71) Applicant: **Deere & Company**, Moline, IL (US)

(72) Inventors: **Thorsten Hagner**, Ilvesheim (DE);
Benjamin Jordan, Ankeny, IA (US);
Aaron Ritter, Milan, IL (US);
Benjamin J. Mueller, Bettendorf, IA (US);
Michael R. Gratton, Asbury, IA (US);
Sebastian Himpel, Mannheim (DE);
Eric Keen, Manhattan, KS (US);
Michael Thompson, Clayton, IN (US);
Mark DePoorter, Coal Valley, IL (US);
Felix Nagelin, Malibu, CA (US);
Nathan R. Demski, Durango, IA (US);
Dean Arden Boyce, Waterloo, IA (US);
Pradipkumar J. Tanpure, Bettendorf, IA (US)

(73) Assignee: **DEERE & COMPANY**, Moline, IL (US)

(**) Term: **15 Years**

(21) Appl. No.: **29/759,479**

(22) Filed: **Nov. 23, 2020**

Related U.S. Application Data

(62) Division of application No. 29/647,298, filed on May 11, 2018, now Pat. No. Des. 915,473.

CLAIM

The ornamental design for an operator station for work vehicle, as shown and described.

DESCRIPTION

FIG. 1 is a front, first side perspective view of an operator station for work vehicle according to one embodiment of our new design;

FIG. 2 is a front elevation view thereof;

FIG. 3 is a rear elevation view thereof;

FIG. 4 is a first side elevation view thereof;

FIG. 5 is a second elevation view thereof;

FIG. 6 is a top plan view thereof;
FIG. 7 is a front, first side perspective view of an operator station for work vehicle as in the FIG. 1 embodiment, shown with surface shading;
FIG. 8 is a front elevation view thereof;
FIG. 9 is a rear elevation view thereof;
FIG. 10 is a first side elevation view thereof;
FIG. 11 is a second elevation view thereof;
FIG. 12 is a top plan view thereof;
FIG. 13 is a front, first side perspective view of an operator station for work vehicle as in the embodiment of FIG. 1, shown without surface shading and with example work vehicle environment in dashed line;
FIG. 14 is a front elevation view thereof;
FIG. 15 is a rear elevation view thereof;
FIG. 16 is a first side elevation view thereof;
FIG. 17 is a second elevation view thereof;
FIG. 18 is a top plan view thereof;
FIG. 19 is a front, first side perspective view of an operator station for work vehicle as in the embodiment of FIG. 1, shown with surface shading and example work vehicle environment in dashed line;
FIG. 20 is a front elevation view thereof;
FIG. 21 is a rear elevation view thereof;
FIG. 22 is a first side elevation view thereof;
FIG. 23 is a second elevation view thereof;
FIG. 24 is a top plan view thereof;
FIG. 25 is a front, first side perspective view of an operator station for work vehicle according to another embodiment of our new design;
FIG. 26 is a front elevation view thereof;
FIG. 27 is a rear elevation view thereof;

FIG. 28 is a first side elevation view thereof;
FIG. 29 is a second elevation view thereof;
FIG. 30 is a top plan view thereof;
FIG. 31 is a front, first side perspective view of an operator station for work vehicle as in the FIG. 25 embodiment, shown with surface shading;
FIG. 32 is a front elevation view thereof;
FIG. 33 is a rear elevation view thereof;
FIG. 34 is a first side elevation view thereof;
FIG. 35 is a second elevation view thereof;
FIG. 36 is a top plan view thereof;
FIG. 37 is a front, first side perspective view of an operator station for work vehicle as in the embodiment of FIG. 25, shown without surface shading and with example work vehicle environment in dashed line;
FIG. 38 is a front elevation view thereof;
FIG. 39 is a rear elevation view thereof;
FIG. 40 is a first side elevation view thereof;
FIG. 41 is a second elevation view thereof;
FIG. 42 is a top plan view thereof;
FIG. 43 is a front, first side perspective view of an operator station for work vehicle as in the embodiment of FIG. 25, shown with surface shading and example work vehicle environment in dashed line;
FIG. 44 is a front elevation view thereof;
FIG. 45 is a rear elevation view thereof;
FIG. 46 is a first side elevation view thereof;
FIG. 47 is a second elevation view thereof; and,
FIG. 48 is a top plan view thereof.

The broken lines illustrate environmental structure that forms no part of the claimed design.
